UNITED STATES PATENT OFFICE

165,059

CONTINUOUS PROCESSING MACHINE FOR BUTTER, MARGARINE, OR SIM- ILAR ARTICLE

Charles Doering and Henry Doering, Chicago, Ill.

Application July 13, 1949, Serial No. 3,888

Term of patent 14 years

(Cl. D55—1)

To all whom it may concern:

Be it known that we, Charles Doering and Henry Doering, citizens of the United States and residents of Chicago, county of Cook, and State of Illinois, have invented a new, original, and ornamental Design for a Continuous Processing Machine for Butter, Margarine or Similar Article, of which the following is a specification, reference being had to the accompanying drawing, forming part thereof.

In the drawing:

Figure 1 is a side view in elevation of a machine for butter, margarine or similar article showing my new design;

Figure 2 is a top plan view thereof; and

Figure 3 is an enlarged end elevational view thereof.

The other side and end of the machine not shown, are substantially plain.

We claim:

The ornamental design for a continuous processing machine for butter, margarine, or similar article, substantially as shown and described.

CHARLES DOERING.

HENRY DOERING.
